PISTON COOLING FOR INTERNAL- COMBUSTION ENGINES

Gustav Pielstick, Saint Germain-en-Laye, France

Application December 30, 1950, Serial No. 203,583
In France May 15, 1950

1 Claim. (Cl. 123—41.35)

1

This invention relates to pistons for internal combustion engines, especially high-powered diesel engines.

The current trend in diesel engine construction is towards increasing values of the mean effective pressure, especially in the case of supercharged 4-cycle engines provided with turbine compressors. Experiments show that such an increase is mainly limited by the operating temperatures in the pistons. Thus, in cylinders having an average bore diameter, at high piston velocities and with an effective mean pressure of 14 kg./sq.cm., the conventional, non-cooled piston made of aluminum alloy was approximately at the limit of its practical possibilities of use. Any further increase beyond such values would require the use of forced cooling for the piston, and this could only be achieved heretofore at the cost of considerable alterations in the piston construction.

It is an object of the present invention to provide an improved piston construction which incorporates new and improved forced cooling means therein. Another object is to provide such a construction which does not entail any considerable modification in the design of the piston itself. A further object is to provide such cooling means which are readily removable and adapted to be removed from one, and mounted on another, piston of standard construction.

With the above and further objects in view, the invention essentially provides a piston with a cooling chamber formed above the piston pin therein, and a generally bell-shaped thin-walled member or jacket removably integrally secured in said piston and pivoted on the piston-pin, having its closed upper end sealing said cooling chamber and extending down with its open lower end around the connecting rod substantially to the lower end of the skirt of the piston, duct means in said jacket member leading to and from said cooling chamber, and inlet and outlet connections at the lower end of said member projecting out of the piston skirt for the circulation of a cooling fluid through said member and said cooling chamber.

The thin-walled jacket member is so constructed as not to hinder the free expansion of the piston. The upper end of the member is seated in an aperture between the recess of the piston skirt and the cooling chamber, defined by an in-turned rib.

2

According to the invention, a standard piston may be constructed for a comparatively wide range of engine power outputs.

An exemplary embodiment of the invention will now be described for purposes of illustration and not of limitation, with reference to the accompanying drawings, wherein:

Fig. 1 is an axial section of a piston constructed according to a preferred form of the invention; 10 Fig. 2 is a section on line II—II of Fig. 1; and Fig. 3 is a section on the broken line III—III of Fig. 1.

As shown in the drawings, the piston 1 is mounted in the usual manner by means of a connecting rod 2 pivoted on the piston pin 3. A hollow jacket member 4, having very thin walls, is inserted in the piston 1 and secured on the piston pin 3. The member 4 terminates at its top at the piston cooling chamber 5, and ducts 6 and 7 in the member 4 lead freely into and from the chamber 5. At its lower end the part 4 is provided with hollow joints 8, 9 which connect the internal space 10, 11 of the part 4 with conduits 12 and 13 through which a cooling fluid may be made to flow.

In operation, when the motor requires a forced cooling for the piston, the cooling fluid is caused to circulate along the path indicated by the arrows f_1, f_2, f_3, f_4 .

The same piston may also be used in connection with a motor operating without the requirement of forced cooling.

Similarly, when the necessity arises of replacing a piston in the motor, the part 4 may be easily removed and mounted on the new piston.

It will be understood that modifications may be made in the details of the embodiment described and illustrated within the scope of the invention.

What I claim is:

In a piston assembly for an internal combustion engine comprising a piston of a usual type, a connecting rod and a piston pin connecting the piston and the connecting rod, an independent inner 45 removable substantially bell-shaped thin walled jacket means with a solid upper portion removably located inside said piston and pivoted about said piston pin, said jacket means defining a completely closed cooling chamber in the upper part 50 of said piston above said piston pin, duct means in said jacket means leading into and out of said

cooling chamber, and fluid-intake and outlet connections at the lower end of said jacket member, providing for a continuous and controlled flow of cooling fluid in said cooling chamber, the said jacket with its related fluid ducts and connections constituting a complete and single assembly adapted for insertion in said piston.

GUSTAV PIELSTICK.
